DISPLAY CARD

Claude Newman, Lincoln, Nebr.

Application August 27, 1941, Serial No. 408,465

3 Claims. (Cl. 40—124.1)

The present invention is concerned with a display card and more particularly with one adapted to be attached to merchandise to indicate the price thereof.

At the present time, it is customary to employ in a store a number of different types of price cards depending upon the type of merchandise to be priced. Thus, in the case of cans, it is often customary to employ a price card which has a supporting loop which surrounds the can. In the case of certain packages, the price cards are provided with flanges adapted to be held between two packages. There are also numerous other types of cards used with various shapes of merchandise.

An object of the present invention is to provide a display card which can be secured to almost any type of merchandise and which will remain rigidly in position when so secured.

A further object of the invention is to provide such a display card which requires no preliminary assembling before being attached to the merchandise.

A further object of the present invention is to provide a pack of display cards of the type set out wherein the individual cards of the pack are held together prior to use by adhesive strips which later serve to affix them to the merchandise.

A further object of the invention is to provide such a display card wherein the card is affixed to the merchandise by a flanged portion coated with a pressure sensitive adhesive.

A further object of the present invention is to provide a display card of the type which can be secured to the surface of merchandise of any normal shape and which at the same time can be employed in connection with the conventional shelf marker strips to call particular attention to certain items on shelves.

Other objects of the present invention will be apparent from a consideration of the accompanying specification, claims, and drawing of which:

Figure 1 is an isometric view of the pack of display cards constituting the present invention;

Figure 2 is an isometric view of the novel display card attached to one of a number of packages in a display pile of packages of merchandise;

Figure 3 is a side elevational view of the display card attached to the package of Figure 2;

Figure 4 is a top plan view of the card attached to a cylindrical object such as a can of merchandise;

Figure 5 is a front elevational view of the card used in connection with the conventional price marker strips; and

Figure 6 is a side elevational view of the card as applied to a shelf with the shelf and the marker strip being shown in section along the line 6—6 of Figure 5.

Referring to Figure 1, I have shown a plurality of my improved display cards secured together in a pack in the form in which they are distributed. It will be noted that each card comprises a body portion 10. This body portion 10 is slotted as at 11, the slot 11 extending down from the upper edge at substantially right angles thereto to provide two tab portions 12 and 13. The body portion 10 is scored as at 14, the line of scoring extending from the left hand edge to a point somewhat above the lower end of slit 11. By reason of this scoring, it is possible to fold 15 the tab 12 out of the plane of the body portion of the card.

It is to be noted that the portions 15 and 16 of the left hand edge of the card, constituting the edge portions of tab 12 and body portion 10 25 respectively, define a plane when the tab 12 is folded out of the plane of the body portion of the card. If the scoring 14 is at right angles to the left hand edge of the card, this plane will be at right angles to the plane of the card. This 30 is the usual arrangement although the invention contemplates the case in which the scoring might be at an angle other than ninety degrees to the left hand edge of the card. In such case, the plane defined by the edges 15 and 16 would form 35 an angle other than ninety degrees with the plane of card 10.

Secured to the left hand edge of the card, including both the main portion 10 and the tab 12, is a tape 18. This tape is an adhesive tape 40 preferably of the type having a coating of a permanently tacky, pressure sensitive adhesive material. The type which has been found desirable for this purpose is that marketed under the trade name of "Scotch" tape. A typical tape of this 45 character is a tape of regenerated cellulose coated with an adhesive of the nature disclosed in Patent No. 1,814,132 to Drew, dated July 14, 1931. As is well known, such an adhesive remains in a permanently tacky state and will cause two objects to adhere together upon pressure being applied to the objects. The adhesive coated tape 18 is secured to the card 10 solely by reason of the adhesive on the surface thereof, this adhesive being on the under side of the tape. It is to 50 be noted that a substantial part of the tape 18

projects beyond the left hand edges of the body portion 10 and the tab 12 of the display card. This projecting part is severed at 19 along a line which forms a continuation of the scoring 14. The result of the slit 19 is that the projecting part comprises two portions 20 and 21 each of which in fact constitutes a flange portion coated with an adhesive material. The tape 18 is preferably sufficiently thin that it can be folded with ease. Consequently, it is very easy to fold the flange portions 20 and 21 out of the planes of the body portion 10 and the tab portion 12.

In attaching the card to a surface, the flange portion 20 is first pressed against the surface to which the card is applied so as to adhere thereto. The main body portion is then folded at right angles to the supporting surface and the tab 12 is then folded out of the plane of the body portion 10, preferably through an angle of about 15 degrees. This is illustrated in Figures 2 and 3 in which the tab 12 has been folded back so as to form with the rear surface of the card an angle of about forty-five degrees. The two projecting portions 20 and 21 of the adhesive coated tape 18 have been secured to the side of package 25 which is the top package of the pile of such packages constituting the sales display. It is to be noted that the body portion 10 of the card is absolutely rigid with respect to the package and that this rigidity is obtained by reason of the manner in which it is attached to the package rather than by any method by which the card is assembled. In other words, the card is rigidly secured to the package by reason of the fact that it is secured along two non-aligned bands which lie within the plane of the surface to which the card is attached.

As indicated in Figure 1, the shape of the card is ideally suited to the pricing of merchandise. The tab 13 provides a conspicuous place for the location of any legends of an explanatory nature. Thus, in the examples shown, the rigid tab 13 has thereon a legend "On Sale Today." The lower portion of the card has a legend indicating the price and provides a space for the application of any other information which may be desired. In actual practice, it is contemplated that the cards will be printed with information similar to that shown in Figure 1. In other words, there will be a group of cards for each sale price. As indicated in Figure 1, these cards are assembled in pad form and are so held together by the projecting parts of adhesive strips 18. Thus, there will be one of these books of pads for each sale price which is normally employed in the store. In pricing the merchandise, all that the store employee must do is to grasp the uppermost card by the right hand end of the body portion 10 and pull it loose from the pad by separating the uppermost adhesive coated tape from the underlying tapes. In pulling the card loose, the projecting edges 20 and 21 tend to be bent forwardly. The projecting edge 20 is now pressed against the merchandise and the body portion 10 is folded forwardly until it is at an angle of ninety degrees with the surface of the merchandise. The tab 12 is then folded backwards. The projecting edge 21 is then bent backwards and pressed against the merchandise. If it is desired to have additional data on the card besides the notation "On Sale Today" and the price, the store employee may write this additional information before removing the card from the pad.

While the card has been shown as affixed to a flat surface, the card can also be attached to a cylindrical surface such as that of a conventional can. Thus, as shown in the top plan view of Figure 4, a card is attached to a can. It will be noted that the projecting edge 20 instead of being bent at right angles is bent at an angle conforming with the curvature of the can 28. It is desirable but not necessary to have the main body portion 10 in front of the diametrical line which is parallel to the plane of the card. Preferably, the card should be so located that this diametrical line approximately bisects the tab 12. When so located, the adhesive flange 21 can be secured to the curved surface of the can with a minimum of buckling. This buckling effect can further be reduced by folding the tab 12 at a sufficiently acute angle with respect to the plane of the main body portion 10 so that the tab 12 traverses only a small angular portion of the can. While the optimum method of securing the tab to a can has been discussed above, actually, the card can be readily secured to a can by affixing it at almost any position below the flange. It will be readily apparent that regardless of what position with respect to the can the card is applied, the flange 20 will adhere to the can throughout its length. Furthermore, it will be obvious that the flange 21 can be made to adhere to the can for a substantial portion of its length thereby giving rigidity to the card.

One of the advantages of the card of the present invention is that it may be used also to mark shelf sales. It is customary to employ in connection with shelving for stores, price card supporting strips comprising a pair of flanges for retaining price cards. Referring specifically to Figures 5 and 6, a shelf is indicated by the reference numeral 30. Secured to this shelf is such a price card indicating strip 31. It will be noted that the upper and lower ends of this strip 31 are turned forwardly to form flanges 32 and 33. Supported on the shelves are a plurality of cans 35 and a plurality of packages 36. A conventional type of price card 37 is shown in Figure 5 in connection with the packages 36 and in Figure 6 in connection with the cans 35. My improved sales price card is shown in connection with the cans 35. It is to be understood that this card is used for indicating when a special price exists on certain articles on the shelves. The card is adapted to be inserted in the flanged strip 31 over the regular price card 37. This is best shown in Figure 6. It will be noted that the folded edge adjacent the scoring line 14 is located under the upper flange 32 and the outermost edge of tab 12 (now the lower edge of the tab) is located under the flange 33. The tab 13 still projects upwardly. It will be noted from Figure 5 that it projects over the actual goods themselves. Where the cards are to be used for this purpose, they are printed with an arrow 39. When so used, this arrow points upwardly to designate that the goods are those resting on top of the shelf to which the marker is attached. After the sale is over, my sale price card can be quickly detached from the price card indicating strip 31 and upon the sales price card being so detached, the regular price card is once more visible.

Because of my price card being so formed that it may be inserted in the regular indicating strips for shelf price cards, it is still further adaptable as a general sales price card. It will thus be seen that I have provided a sales price card which can be used in almost all types of applications

encountered in a store. Regardless of whether it is to be applied directly to the goods or to price card retaining strips, the card can be quickly attached and detached.

While I have shown a specific embodiment of the invention for purposes of illustration, it is to be understood that the invention is limited only by the scope of the appended claims.

I claim:

1. A display card comprising a card having a slot extending inwardly from a first edge for a short distance to provide two tab portions, said card being scored from a second edge to said slot along a line perpendicular to said second edge so as to facilitate the folding of one of said tab portions out of the plane of the card, said card having a flange portion coated with a pressure sensitive adhesive and extending from said second edge of both said card and said folding tab, said flange portion being severed adjacent the line of scoring to form two parts which can be folded about said second edge into the plane defined by said second edge of said main card and folding tab when said tab is folded out of the plane of said card.

2. A display card comprising a card having a slot extending inwardly from a first edge for a short distance to provide two tab portions, said card being scored from a second edge to said slot along a line perpendicular to said second edge so as to facilitate the folding of one of said tab portions out of the plane of the card, and

- 5 a flange portion formed of a flexible tape coated with a pressure sensitive adhesive and secured to said card and said folding tab along said second edge with a portion projecting beyond said edge, the projecting portion of said tape being severed adjacent the line of scoring to form two parts which can be folded about said second edge into the plane defined by said second edge of said main card and folding tab when said tab is folded out of the plane of said card.
- 10 3. A pack of display cards, each card having a slot extending inwardly from a first edge for a short distance to provide two tab portions, each card being scored from a second edge to said slot along a line perpendicular to said second edge so as to facilitate the folding of one of said tab portions out of the plane of the card, and a flange portion formed of a flexible tape coated with a pressure sensitive adhesive and secured to each card and folding tab along said second edge with a portion projecting beyond said second edge, the projecting portion of said tape being severed adjacent the line of scoring so as to be adapted to be folded into the plane defined by
- 15 20 25 30 said edge of said main card and folding tab when said tab is folded out of the plane of said card, and the projecting portions of the tapes of the several cards of the pack being superposed and pressed together so as to hold the cards detachably in pack form.

CLAUDE NEWMAN.
